UNITED STATES PATENT OFFICE

EDGAR M. SORENG, OF CHICAGO, ILLINOIS, ASSIGNOR TO SORENG-MANEGOLD COMPANY,
OF CHICAGO, ILLINOIS, A CORPORATION OF ILLINOIS

DESIGN FOR A PORTABLE WATER SOFTENER

Application filed August 5, 1932. Serial No. 44,530. Term of patent 3½ years.

To all whom it may concern:

Be it known that I, EDGAR M. SORENG, a citizen of the United States, residing at Chicago, in the county of Cook and State of Illinois, have invented a new, original, and ornamental Design for Portable Water Softener, of which the following is a specification, reference being had to the accompanying drawing, forming part thereof.

I claim:

The ornamental design for a portable water softener, as shown.

EDGAR M. SORENG.
